United States Patent Office

Des. 223,731
Patented May 30, 1972

223,731

COMBINED TYPEWRITER, RECORDING DEVICE AND ENCLOSURE THEREFOR

Clarence D. Zierhut, 16909 Flanders,
Granada Hills, Calif. 91344

Filed Sept. 30, 1970, Ser. No. 22,244

Term of patent 14 years

Int. Cl. D18—01

U.S. Cl. D64—11

FIG. 1 is a perspective view of a combined typewriter, recording device and enclosure therefor showing my new design;

FIG. 2 is a left side elevational view;

FIG. 3 is a rear elevational view;

FIG. 4 is a perspective view of a combined typewriter, recording device and enclosure therefor showing another form of my new design wherein the recording device includes a pair of spaced apart circular elements;

FIG. 5 is a left side elevational view thereof; and

FIG. 6 is a rear elevational view thereof.

I claim:

The ornamental design for a combined typewriter, recording device and enclosure therefor, substantially as shown and described.
